UNITED STATES PATENT OFFICE.

AXEL H. ENGLUND, OF PHILADELPHIA, PENNSYLVANIA.

DESIGN FOR A RAIL-BOND.

SPECIFICATION forming part of Design No. 34,716, dated July 2, 1901.

Application filed March 23, 1901. Serial No. 52,656. Term of patent 14 years.

To all whom it may concern:

Be it known that I, AXEL H. ENGLUND, a citizen of the United States, residing at the city of Philadelphia, in the county of Philadelphia and State of Pennsylvania, have invented and produced a new and useful Design for a Rail-Bond, of which the following is a specification, reference being had to the accompanying drawings, forming part hereof, in which—

Figure 1 is a front elevational view of a rail-bond, showing my design. Fig. 2 is a rear elevational view of said bond, and Fig. 3 is a top or plan view thereof.

My design relates to that special class of rail-bonds consisting of end studs and a number of flat connecting-strips arranged face to face in a single group, the bodies of which connecting-strips exist in a plane perpendicular to the axes of the studs as distinguished from the type or class in which the strips are arranged in two oppositely-disposed groups, as well as from the class in which the strips when in a single group are curved outward in the plane of the axes or bodies of the end studs.

The leading or material feature of my design consists in the peculiar form of curvature of the group of connecting-strips and the especial relation established between the curves of said connecting-strips and the end studs.

Referring to the drawings, *a* represents a series of flat nested strips connecting the end studs *b*, all arranged in a single group in a plane perpendicular to the axes of the bodies of the end studs. The strips of the group embody two approximately straight portions *a'*, connected by the curved upwardly-pro-

jecting portions *a²*, the uppermost strand included in said curved portion describing a semicircle, as shown at *a³*, and merging at either end through the concave or curved necks *a⁴* into the straight portions *a'*. The lowermost strand or strip is as to its region *a²*, also semicircular, as shown at *a⁵*, but formed on a radius proportionately smaller than that of the uppermost strand, and it merges on either side into the portions *a'* by or through curved portions *a⁶*, formed on a radius much larger than that of the curved necks *a⁴*. The intermediate strips are curved concentrically with respect to the upper and lower strips referred to. The end studs *b* are provided with bodies *b⁴* and with flat heads which are arranged with their upper edges in a common plane tangential to the top of the curved portion *a³* of the uppermost strand or strip of the group. The front and rear faces of the heads of the end studs are in parallelism and in planes perpendicular to the axes of the bodies of the studs. The portions *a'* are as to their outer ends provided with upwardly-curved portions *a⁷*, which merge into the lower edges of the heads of the end studs.

Having thus described my invention, what I claim as new, and desire to secure by Letters Patent, is—

The design for a rail-bond, substantially as herein shown and described.

In witness whereof I have hereunto set my signature, this 22d day of March A. D. 1901, in the presence of two subscribing witnesses.

AXEL H. ENGLUND.
